UNITED STATES PATENT OFFICE.

GEORGE P. WIGGINTON, OF KALAMAZOO, MICHIGAN.

DESIGN FOR A DESK.

55,497.

Specification for Design.

Patented June 15, 1920.

Application filed December 19, 1919. Serial No. 346,186. Term of patent 14 years.

To all whom it may concern:

Be it known that I, GEORGE P. WIGGINTON, a citizen of the United States, and a resident of the city and county of Kalamazoo, State of Michigan, (whose post-office address is Kalamazoo, Michigan, % Kalamazoo Loose Leaf Binder Company,) have invented a new, original, and ornamental Design for Desks, of which the following is a specification, reference being had to the accompanying drawing, forming a part thereof, which is a front perspective view of a desk showing my new design.

I claim:

The ornamental design for a desk as shown.

GEORGE P. WIGGINTON.
